(57) **CLAIM**

An ornamental design of a mobile device wireless audio link, as shown and described.

DESCRIPTION

FIG. 1 is a top front left side perspective view of a mobile device wireless audio link according to our design;

FIG. 2 is a bottom back right side perspective view of the mobile device wireless audio link;

FIG. 3 is a front side perspective view of the mobile device wireless audio link;

FIG. 4 is a right side perspective view of the mobile device wireless audio link;

FIG. 5 is a back side perspective view of the mobile device wireless audio link;

FIG. 6 is a left side perspective view of the mobile device wireless audio link;

FIG. 7 is a top side perspective view of the mobile device wireless audio link; and,

FIG. 8 is a bottom side perspective view of the mobile device wireless audio link.

The dashed lines shown in the various figures are provided for the purpose of illustrating unclaimed portions of the mobile device wireless audio link. The dashed lines form no part of the claimed design.
